CLAIM

The ornamental design for an electronic device, as shown and described.

DESCRIPTION

FIG. 1 is a front perspective view of an electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the portion 9 encircled in dot-dot-dashed broken lines in FIG. 1;

FIG. 10 is an enlarged view of the portion 10 encircled in dot-dot-dashed broken lines in FIG. 1;

FIG. 11 is an enlarged view of the portion 11 encircled in dot-dot-dashed broken lines in FIG. 2;

FIG. 12 is an enlarged view of the portion 12 encircled in dot-dot-dashed broken lines in FIG. 3;

FIG. 13 is an enlarged view of the portion 13 encircled in dot-dot-dashed broken lines in FIG. 4;

FIG. 14 is an enlarged view of the portion 14 encircled in dot-dot-dashed broken lines in FIG. 5;

FIG. 15 is an enlarged view of the portion 15 encircled in dot-dot-dashed broken lines in FIG. 6;

FIG. 16 is an enlarged view of the portion 16 encircled in dot-dot-dashed broken lines in FIG. 7;

FIG. 17 is an enlarged view of the portion 17 encircled in dot-dot-dashed broken lines in FIG. 8;

FIG. 18 is an enlarged view of the portion 18 encircled in dot-dot-dashed broken lines in FIG. 8;

FIG. 19 is an enlarged view of the portion 19 encircled in dot-dot-dashed broken lines in FIG. 8; and,

FIG. 20 is an enlarged view of the portion 20 encircled in dot-dot-dashed broken lines in FIG. 8.
